UNITED STATES PATENT OFFICE

ROY E. DEEBLE, OF LONG BEACH, CALIFORNIA

INTERNAL COMBUSTION ENGINE

Application filed October 25, 1929. Serial No. 402,455.

This invention relates to an engine construction in which a novel combination of elements give rise to a desirable, light weight machine of numerous uses. For example, the 5 construction disclosed herein may be employed in double-acting internal combustion engines so as to give rise to a motor capable of generating an increased quantity of power for a given weight of machinery.

10 The invention relates to a construction of cylinders and pistons which permits space heretofore wasted to be utilized either in the generation of power or in the compression of fuel or air for use in the motor.

15 Generally described, the invention relates to a reciprocating engine in which a movable piston provided with a skirt and with a longitudinal opening in the skirt is employed. A wrist pin assembly may be removably attached to the lower end of the piston skirt, namely, to the end of said skirt opposite the head of the piston.

20 A stationary bulkhead is then preferably positioned within the piston skirt, that is, the bulkhead is stationary with respect to the cylinder in which the piston is located and around which the piston skirt may be moved. An expansible shoe packing is preferably carried by the stationary bulkhead, 25 said packing extending through the opening in the piston skirt so as to seal this opening substantially gas-tight.

The construction described in general hereinabove gives rise, therefore, to a cylinder 30 containing a movable piston and with chambers on both sides of the piston, so that two expansion chambers are formed in each cylinder. These expansion chambers are of substantially the same volume or diameter.

35 By placing a valve assembly in operative communication with the space between the stationary bulkhead and the head of the cylinder through the longitudinal opening in the skirt of the piston, the motor may be used as a 40 double-acting internal combustion or reciprocating engine.

45 Instead of using the space between the movable piston and the stationary bulkhead as an expansion chamber, said chamber may be 50 employed as a compression chamber, such as

for example, a chamber in which air or a mixture of gases adapted to be used as a fuel may be compressed and then injected into the upper portion of the cylinder. In this manner the engine will function as a single 55 acting motor, the lower chamber fulfilling merely the purposes of a super-charger or fuel compressor.

Another object of this invention is to disclose and provide a reciprocating engine in which 60 means are provided for maintaining a movable piston in perfect alinement with the cylinder walls.

Another object of this invention is to disclose and provide an internal combustion engine of the double-acting type. 65

A still further object of this invention is to disclose and provide a new and novel wrist pin assembly for movable pistons.

Another object is to disclose and provide a 70 novel method of supplying cooling fluid to pistons while they are in motion.

A still further object is to disclose and provide a reciprocating engine in which work is performed on both the up and down strokes 75 of the piston.

Another object is to disclose and provide a simplified construction for double-acting internal combustion engines.

Another object is to disclose and provide a 80 double-acting internal combustion engine in which means for sealing the piston against the passage of gases thereby is provided.

Other objects and advantages of my invention will become apparent to those skilled in the art from the following detailed description of the preferred form of my invention and modifications thereof, reference being had to the appended drawings, in which for 85 illustrative purposes, a double-acting, four-stroke cycle internal combustion engine is shown.

90 It is to be understood, however, that the invention is not limited to its adaptation and use on four-stroke, double-acting internal combustion engines, but may be applied to other purposes and uses.

95 In the drawings:

100 Fig. 1 is a longitudinal section through one

cylinder of an internal combustion engine embodying my invention.

Fig. 2 is a side elevation, partly in section, of the movable piston and stationary bulkhead employed in Fig. 1.

Fig. 3 is a perspective showing one form of expandible shoe packing employed in sealing the port of the movable piston in Figs. 1 and 2.

Fig. 4 is a contraction ring used in the motor illustrated in the other figures.

Fig. 5 is a horizontal section taken on the plane 5—5 indicated in Fig. 1.

Fig. 6 is a horizontal section taken along the plane 6—6 of Fig. 1.

Fig. 7 is a horizontal section taken along the plane 7—7 of Fig. 1.

Fig. 8 is a horizontal section taken along plane 8—8 of Fig. 1.

Fig. 9 is a longitudinal section through one cylinder, showing an internal combustion engine embodying a modification of my invention.

Fig. 10 is a transverse section along the plane 10—10 of Fig. 9.

Fig. 11 is a longitudinal section through a portion of a cylinder disclosing a modified form of construction used in positioning the stationary bulkhead.

Fig. 12 is a transverse section taken along the plane 12—12 shown in Fig. 11.

Referring to Fig. 1, the double-acting engine shown therein is of a type which is particularly adapted for smaller engines such as automobile, motorcycle and airplane engines. It is to be understood that the construction shown in the illustrative examples described hereinafter is not only applicable to internal combustion engines of the type given, but may also be employed in the construction and assembly of various other types of reciprocating engines such as for example, Diesel engines, certain types of reciprocating engines and the like.

The engine may comprise an upper cylinder portion 1 connected in any suitable manner as by means of the bolts 2 to a lower cylinder portion 3, so as to form one continuous cylinder having an inner wall, indicated at 4. The upper portion of the cylinder 1 may be provided with a closed head indicated at 5, and a valve chamber 6 may be in communication with the upper portion of the cylinder 1. A similar valve chamber 7 may be in communication with an intermediate portion of the cylinder, as for example between cylinder portions 1 and 3. Spark plugs 8 and 8' may be provided in the respective valve chambers 6 and 7, and suitable valves 9 and 9' may be operatively positioned in the valve chambers 6 and 7, said valves 9 and 9' being preferably actuated from a common cam shaft 10.

It is to be understood that although only one valve is shown in each of the valve chambers 6 and 7, other valves are provided in ac-

cordance with customary design, so that an intake valve and an exhaust valve is positioned in each valve chamber.

The lower portion of the cylinder, namely, the portion 3 may be connected to a crank case 11 in any suitable manner, as for example by means of the bolts 12. Within the cylinder 1 a movable piston may be positioned, said piston as indicated in Fig. 1, consisting of a hollow head 13, a skirt 14 and a wrist pin assembly, generally indicated at 15. Said wrist pin assembly is attached to the end of the skirt 14 of the movable piston. Suitable expansion rings 16 may be carried by the hollow head 13 of the movable piston, and a longitudinal port or opening 17 is preferably formed in the skirt 14 of the movable piston. The valve chamber 7 communicates with the interior of the cylinder through the port 17 in the piston skirt 14.

A stationary bulkhead 18 is preferably positioned within the skirt 14 of the movable piston and between the wrist pin assembly 15 and the hollow head 13 of said piston. As shown in Fig. 1, the stationary bulkhead 18 is in general of an outside diameter substantially equivalent to the internal diameter of the piston skirt 14.

The stationary bulkhead 18 may be firmly attached to the cylinder portion 3 by means of a downwardly extending member 19 in alignment with the edges of the port 17 formed in the piston skirt 14, said member 19 being attached to the cylinder portion 3 in any suitable manner, as for example by means of the machine screws 20. In addition, the stationary bulkhead 18 may be provided with a member 21 extending through the port 17 into the valve chamber 7 so as to permit said member 21 to be connected to the flange or web 22 of the body member 3, by means of machine screws or other suitable means 23.

As more particularly shown in Fig. 5, a certain amount of space is left between the inner surface 4 of the cylinder, the outer surface of the stationary bulkhead 18 and the edges of the port 17 of the split skirt. Leakage of gases would occur through this segmental opening. Means have been provided for preventing such leakage, and such means comprise a segmental expandible shoe packing carried by the stationary bulkhead 18. The segmental shoe packing is shown in perspective in Fig. 3, in section in Fig. 1, in side elevation in Fig. 2, and in transverse section in Fig. 6. As shown in the drawings, and particularly Fig. 3, the segmental packing may comprise two segmental portions 24 and 24' having opposed fingers capable of causing engagement between the sections 24 and 24' in an interlocking manner. The segments 24 and 24' may be provided with edges 17a adapted to contact with the edges 17 of the port formed in the split skirt 14.

Each of the segments 24 and 24' may be provided with internally extending portions 25 and 25', said portions being adapted to be received in a groove formed in the stationary bulkhead 18. The internally extending members 25 and 25' follow the curvature of the stationary bulkhead 18 and extend into the grooves formed in said bulkhead beyond the port 17 formed in the split skirt. The segments 24 and 24' are maintained in position on said bulkhead and the edges 17a of said segments are maintained in contact with the edges of the port 17 by means of an expansion ring 26 provided with lugs 27, said lugs being adapted to be received in recesses 28 formed in the members 25 and 25'. Circular expansion rings of any suitable type, such as the rings 29, may also be carried by the bulkhead 18, said rings 29 being preferably so positioned as to cover the overlapping edges of the interengaging tongue members carried by the segments 24 and 24'.

The rings 29 may be of the type shown in Fig. 4, the distinguishing characteristic of said rings being a plurality of tangentially positioned grooves 30 in the edges of said rings. The purpose of said tangential grooves 30 is to cause said ring 29 to partially rotate whenever gases in compression leak past said ring, such rotation being imparted to the ring by reason of the force of gases impinging upon the angularly disposed grooves, the resultant force tending to rotate the rings, thereby preventing the formation of carbon or other impurities on the ring and the sticking or freezing of the ring in one position. A more even wear is obtained in this manner.

Contraction rings 31 may be positioned in suitable grooves formed in the cylinder portion 3, said grooves and contraction rings being substantially in the plane of the bulkhead 18 and preferably so positioned as to cover the inter-engaging fingers carried by the segmental portions 24 and 24' of the segmental packing carried by the stationary bulkhead. These contraction rings 31 may also be provided with tangentially positioned grooves in their upper edge so that they resemble the expansion rings 29 in this manner.

The wrist pin assembly 15 may be removably connected to the lower edge of the piston skirt 14 and may include a wrist ring 32 provided with wrist pin bosses 33 adapted to receive a wrist pin 34 which in turn is connected by means of a connecting rod 35 with a suitable crank shaft 36 mounted in bearings 37. The wrist ring 32 has an outer diameter substantially equivalent to the inner diameter of the piston skirt 14. The wrist ring 32 may be provided with a plurality of lugs 38 which preferably are in the shape of a tenon. The piston skirt 14 may be provided with a plurality of bayonet slots 39 adapted to receive the lugs 38 and thereby prevent a relative longitudinal motion be-

tween the wrist ring 32 and the piston skirt 14 when said lugs 38 are in position in said bayonet slots 39.

Means for locking the wrist ring 32 in position in said bayonet slots 39 may include a locking ring 40 provided with means adapted to receive and center the lower edge of the piston skirt 14. Such centering means may include a small step or flange formed in the bottom edge of the piston skirt 14, and a groove in the locking ring 40 adapted to receive such flange, as is generally indicated at 41. In order to prevent rotation of the locking ring 40 with respect to the piston skirt 14, the locking ring 40 may carry a lug 42 adapted to be received in a slot formed in said piston skirt, such as for example, one of said bayonet slots 39.

The wrist ring 32 may be provided with a plurality of bosses 43 having internally threaded surfaces adapted to receive bolts 44 passing through apertures formed in the locking ring 40, said apertures being in alignment with the bosses 43 when the lug 42 carried by said locking ring 40 is in position in one of said slots. It will be thus seen that means have been provided for removably connecting a wrist pin assembly to the piston skirt 14 without necessitating the removal of the bulkhead 18 or of the piston from the cylinder, the replacement of wrist pin assemblies being accomplished through the crank case of the motor when desired.

A modified form of construction is shown in Fig. 9. It will be seen that the stationary bulkhead 18 instead of being directly connected to the cylinder portion 3, as by means of a member 19 shown in Fig. 1, is in the form of a piston provided with two split skirts or skirt portions 45 and 45'. The split skirt 45 extends along the inner surface 4 of the cylinder in substantial extension of the port 17 formed in the split skirt 14 of the movable piston. The split skirt portion 45' is spaced from the inner surface 4 of the cylinder a distance somewhat in excess of the thickness of the skirt 14. The skirt portions 45 and 45' may be connected to a ring 46 which in turn is connected to a member 47 as by means of machine screws 48. The member 48 may then be connected to the crank case 11 and to the cylinder portion 3 by means of suitable bolts 49. In this manner the stationary bulkhead 18 is maintained in position within the skirt 14 of the movable piston.

Packing shoes, similar to those employed on the stationary bulkhead shown in Fig. 1, may be employed on the bulkhead described and shown in Fig. 9, said shoes fitting between the edges 17 of the longitudinal port or opening formed in the skirt 14 of the movable piston. As shown in Fig. 10, the wrist pin bosses 33' may be formed integrally or firmly attached to the ends of the skirt 14 of the movable piston.

As shown in Fig. 9, the hollow head 13' may be provided with means for supplying cooling fluid thereto. It will be noted that if the construction described hereinabove is used in the manufacture of internal combustion double-acting engines, two explosion and expansion chambers are formed, one on each side of the movable piston head 13', namely, the chambers A and B. The piston head is, therefore, subjected to a high heat and it is desirable to provide cooling means therefor.

Such cooling means may comprise a tubular member 51 extending upwardly from the head 13' of the cylinder and being desirably connected thereto as by means of a threaded joint 52 which may be spot-welded in place. A telescopic connection may then be made between the hollow head 13' and said tubular member 51, as by means of a conduit 53 connected to the hollow head 13' as by means of a threaded connection 54. The member 53 is preferably slidably received in the tubular member 51 and is of relatively small diameter. Contraction rings 55 may be provided in the tubular member 51 so as to prevent leakage of gases through the tubular member 51.

Means for admitting cooling fluid through the telescopic connection described hereinabove into the hollow head 13' may include a pipe or conduit 56 passing through a suitable connection 57 in the tubular member 51 and extending through the tubular member 53 into the hollow head 13', when said hollow head 13' is in its highest position. Cooling fluid (such as oil) thus supplied to the hollow head 13' may be withdrawn through the conduit 53 and tubular member 51, through a suitable connection 58.

It is desirable to employ a check valve in line 58 and if necessary a similar check valve in line 56, so as to prevent a churning action from being set up when the piston head 13' is in motion, but instead to maintain a circulation of cooling fluid through said hollow head.

As shown in Fig. 9, the hollow head 13' may be removably connected to the skirt 14. The hollow head 13' may be provided with a downwardly extending flange 59 internally threaded so as to engage with a locking ring 60 which is externally threaded and forms a threaded connection indicated at 61. The locking ring 60 may be provided with an outwardly extending flange 62 adapted to cooperate with a key 63 seated in a groove or key-seat formed on the internal surface of the skirt 14. The upper edge of the skirt 14 may be provided with a flange adapted to seat in a groove formed in the flange 59 of the hollow head 13'. It will thus be seen that by rotating the ring 60 so as to form a threaded engagement of said ring with the hollow head 13', as indicated at 61, the skirt 14 will

be held in contact with the head 13' and rendered substantially unitary therewith.

The modification shown in Fig. 11 resembles the construction shown in Fig. 1. The stationary bulkhead 18' consists of a circular portion having an outer diameter substantially equivalent to the inner diameter of the skirt 14. Said bulkhead 18' is maintained in position within the cylinder and within the skirt 14 by means of an upper plate 75 or member 64 which passes through the longitudinal port 17 of the skirt 14, and is attached to the bottom of the valve chamber 7 and to the top of the stationary bulkhead 18' in any suitable manner, as for example, by means of the machine screws 65.

Said stationary bulkhead 18' may also be maintained in its position by means of a supporting member 66 provided with a downwardly extending member 67 extending through the longitudinal opening 17 in the piston skirt 14, into a key-seat 68 formed in the inner surface 4 of the cylinder portion 3. The member 66, together with its member 67 may thus be maintained in position 90 within the cylinder by means of machine screws or bolts 69 without interrupting the continuous circular form of the cylinder walls. It is to be understood that the member 66 is connected to the bulkhead 18' by 95 means of suitable machine screws 70 and that the bulkhead 18' is provided with suitable expansion shoe packing fitting into the port 17 of the skirt 14.

Preferably, the top member 64 is of such 100 size as to permit its being introduced through the port 17 of the piston skirt 14 and then turned through an angle of about 90 degrees without scraping the inner surfaces of the piston skirt.

Details of intake and exhaust valve mechanism have not been shown in the drawings, as their construction and arrangement is well known in the art. Furthermore, it is to be understood that the type of packing rings 110 used in the movable piston and exteriorly of the stationary bulkhead may be varied within wide limits.

Although a particular form of expandible shoe packing has been described herein, the 115 invention is not limited to such particular form as any segmental packing capable of fitting between edges of a longitudinal port in a piston skirt is included as coming within the scope of this invention. Furthermore, the provision of cooling means for the movable piston head may or may not be employed, nor is the invention limited to the employment of a removable wrist pin assembly as disclosed hereinabove, but instead includes all 120 such modifications and changes as come within the scope of the appended claims.

Furthermore, it is to be understood that it is not essential that both the upper and lower chambers, that is, the chambers A and 130

B on either side of the movable piston, be employed as explosion chambers. Instead, one of said chambers, such as for example the chamber B between the movable piston and 5 the stationary bulkhead, may be employed for compressing air or other gaseous fuel for purposes of injection into the explosion chambers A. Other uses of this invention will become apparent to those skilled in the art from 10 the description given hereinabove.

I claim:

1. In a reciprocating engine, the combination of a cylinder, a movable piston within said cylinder, said piston including a head, 15 a skirt and a single longitudinal opening in said skirt, and a stationary transverse bulkhead positioned within said skirt and within said cylinder, said bulkhead being provided with a single shoulder extending longitudinally of said cylinder and connected to the cylinder at points within the longitudinal opening in said piston skirt.
2. In an internal combustion engine, the combination of a cylinder, a movable piston within said cylinder, said piston being provided with a head, a skirt and a single longitudinal opening in said skirt, and a stationary transverse bulkhead within said piston skirt, said bulkhead being connected to the 25 cylinder by means of a member extending through said longitudinal opening in said piston skirt into contact with the cylinder wall and also extending longitudinally of said cylinder wall in a direction away from the head of said piston.
3. In an internal combustion engine, the combination of a cylinder, a movable piston within said cylinder, said piston being provided with a head, a skirt and a longitudinal 30 opening in said skirt, a stationary bulkhead within said piston skirt and cylinder, said bulkhead being connected to the cylinder by means of a member extending through said longitudinal opening in said piston skirt, an expandible shoe mounted on said bulkhead and fitting into the longitudinal opening in said movable piston, and contraction rings in said cylinder externally of said piston skirt and substantially in the plane of said bulkhead.
4. In a piston assembly, the combination of a piston skirt, a piston head provided with a downwardly extending flange, a groove in said flange adapted to receive the edge of the 45 piston skirt, threads cut on the internal surface of said flange, a key seat in the internal surface of said skirt, a key in said seat, and an externally threaded locking collar provided with an outwardly extending flange adapted 50 to cooperate with said internally threaded head flange and said skirt key to hold said head and skirt together.
5. In an internal combustion engine, the combination of a cylinder, a movable piston 55 in said cylinder, said movable piston being provided with a head, a skirt and a single longitudinal opening in said skirt, a stationary transverse bulkhead within said piston skirt, a valve port in said cylinder in communication with the space between said piston head and bulkhead through said longitudinal opening, and a second valve port in said cylinder in communication with the space between said piston head and cylinder head.
6. In an internal combustion engine, the combination of a cylinder, a movable piston within said cylinder, said piston being provided with a head, a skirt and a longitudinal opening in said skirt, a stationary transverse bulkhead within said piston skirt, a valve port in said cylinder in communication with the space between said piston head and bulkhead through said longitudinal opening, and means for supplying a cooling fluid to said head while said piston is in motion, said means including a tubular member extending from the top of said cylinder, a telescopic connection between said tubular member and hollow head, and means for supplying cooling fluid to said hollow head through said telescopic connection and withdrawing fluid from said tubular member.
7. In a reciprocating engine, the combination of a cylinder provided with a head, a movable piston within said cylinder, said piston being provided with one open end, a head, a skirt, and a longitudinal opening in said skirt, a stationary transverse bulkhead within said piston skirt, said bulkhead being connected to the wall of said cylinder by means of a member extending radially from said bulkhead through said piston skirt opening into contact with said cylinder wall, and then said member extending along said cylinder wall toward the open end of said piston, a valve port in said cylinder in communication with the space between said piston head and bulkhead through said longitudinal opening, and a second valve port in said cylinder in communication with the space between said piston head and cylinder head.
8. In a reciprocating engine, the combination of a cylinder provided with a head, a movable piston within said cylinder, said piston being provided with one open end, a head, a skirt, and a longitudinal opening in said skirt, a stationary transverse bulkhead within said piston skirt, a valve port in said cylinder in communication with the space between said piston head and bulkhead through said longitudinal opening, said bulkhead being connected to the wall of said cylinder by means of a member extending through said valve port and longitudinal piston skirt opening and connected to said bulkhead, and a member extending radially from said bulkhead through said skirt opening into contact with the cylinder wall, and then along said

cylinder wall toward the open end of said piston.

9. In a reciprocating engine, the combination of a cylinder provided with a head, a movable piston within said cylinder, said piston being provided with one open end, a head, a skirt, and a longitudinal opening in said skirt, a stationary transverse bulkhead within said piston skirt, a valve port in said cylinder in communication with the space between said piston head and bulkhead through said longitudinal opening, said bulkhead being connected to the wall of said cylinder by means of a member extending through said valve port and longitudinal piston skirt opening and connected to said bulkhead, a member extending radially from said bulkhead through said skirt opening into contact with the cylinder wall, and then along said cylinder wall toward the open end of said piston, an expansible shoe carried by said bulkhead and fitting into the longitudinal opening in said movable piston, and contraction rings in said cylinder externally of said piston skirt and substantially in the plane of said bulkhead.

10. In a reciprocating engine, the combination of a cylinder provided with a head, a movable piston within said cylinder, said piston being provided with one open end, a head, a skirt, and a longitudinal opening in said skirt, a stationary transverse bulkhead within said piston skirt, a valve port in said cylinder in communication with the space between said piston head and bulkhead through said longitudinal opening, a valve assembly in operative communication with said valve port, a member connected to said bulkhead and extending through said valve port and piston skirt opening into said valve assembly and connected thereto, a member extending radially from said bulkhead through said skirt opening into contact with the cylinder wall and then along said cylinder wall toward the open end of said piston, means for connecting said latter member and cylinder wall, an expansible shoe carried by said bulkhead and fitting into the longitudinal opening in said movable piston, contraction rings in said cylinder externally of said piston skirt and substantially in the plane of said bulkhead, and a second valve port in said cylinder in communication with the space between said piston head and cylinder head.

Signed at Los Angeles, Calif., this 15th day of October, 1929.

ROY E. DEEBLE.
